STOPPER POLISHING MACHINE

Norman R. Beck, Baltimore, Md., assignor to
Carr-Lowrey Glass Co., Baltimore, Md.

Application February 8, 1933, Serial No. 655,841

8 Claims. (Cl. 51—95)

This invention relates to machines for polishing glass stoppers such as used in bottles and it is designed primarily for polishing the edges of the heads of stoppers. Heretofore the polishing of the edges of stopper heads has been a costly item in the production of finished glass stoppers and the present invention has for an object the provision of means whereby it is possible for one person to handle a much greater number of stoppers in a given time than has heretofore been possible.

It is another object of the invention to provide a simple and efficient mechanism whereby more than one stopper can be polished at one time, suitable equalizing means being employed whereby all of the stoppers will be maintained constantly in proper working relation with their polishing wheels during the polishing operation.

A still further object is to shift the stoppers automatically relative to the polishing surfaces so as to distribute wear over said surfaces and prevent the formation of undesirable channels resulting from abrasion.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings:

Figure 1 is a front elevation of the apparatus, portions being broken away.

Figure 2 is an elevation showing one side of the structure illustrated in Figure 1, a portion being broken away.

Figure 3 is an elevation showing the opposite side of the structure.

Figure 4 is an enlarged section through a portion of one of the rocker heads and its spindle, a stopper being shown in engagement therewith.

Referring to the figures by characters of reference 1 and 2 designate side frame members each of which is provided with an adjustable bearing block 3 engaging the tapered ends 4 of a shaft 5.

On the shaft are arranged polishing wheels 6 disposed in pairs. The shaft also carries a pulley 7 adapted to receive motion from any suitable source through a belt 8 or the like.

The frame member 1 has an upwardly projecting extension 9 joined by an angle strip 10

to a similar extension 11 projecting upwardly from the frame member 2. A head 12 is secured to the extension 9 and provides a bearing 13 for a shaft 14 to which is secured a worm gear 15 and a toothed gear 16. Another bearing 17 is provided for the shaft 18 of a toothed gear 19 and a cam 20.

The worm gear 15 engages a worm 21 in which is feathered a shaft 22 provided with a collar 23 having an annular groove 24. A lever 25 is fulcrumed at 26 on a bracket 27 secured to extension 9 and this lever has a looped portion 28 extending loosely around the collar 23 and provided with pins 29 working in the groove 24. The upper end of lever 25 is yieldingly restrained by a spring 30 attached to a bracket 31 and extending from the lever is an arm 32 having a roller 33 engaging the edge of the cam 20.

One end of shaft 22 telescopes into a sleeve 34 carried by an extension 35 of shaft 22. The shaft 22 is slidable within sleeve 34 but rotates therewith, any suitable driving connection being provided such as a slot 36 and a pin 37.

The shaft extension 35 is journaled in a housing 38 supported by a bracket 39 on extension 11. A worm gear 40 is secured to the shaft extension and rotates within the housing. It receives motion through a worm 41 from the shaft 42 of a motor 43. Thus the worm and its gear constitute a speed reduction mechanism for submitting motion from the motor to shaft 35—22.

Mounted to swing on the shaft 22 is the forked end 44 of an arm 45, this arm being held against sliding movement relative to shaft 22 by any suitable means, such as collars 46. A pulley 47 is secured to shaft 22 within the fork 44 and adjacent to the fork is a bracket 48 carrying an idler pulley 49. The idler pulley is adjustably mounted as shown in Figure 3 so as to constitute a belt tightener, the bearing 50 of the pulley being adjustably clamped in slots 51 formed in the bracket 48.

The bracket 48 is extended backwardly from arm 45 and has a latch lever 52 pivotally mounted thereon at 53. The upper end of this latch lever has a notch 54 normally positioned above the angle strip 10 and a spring 55 serves to pull the latch lever against the strip 10.

Arm 45 has a rocker head 56 swivelled therein at its lower end and this rocker head is formed with an opening 57 in which is mounted a pulley 58. The pulley is secured to a spindle 59 extending transversely of and journaled within the rocker head. The spindle is tubular as shown for example in Figure 4 and the ends of the 110

bore in the spindle are slightly flared as indicated at 60 so as to be snugly engaged by the tapered portion T of a strip S.

Handle 61 extends from the rocker head and 5 fulcrumed adjacent thereto is a hand lever 62 connected by a rod 63 to the lower end of latch lever 52.

A drive belt 64 is mounted on the pulleys 47, 49 and 58 and serves to transmit motion from 10 shaft 22 to the spindle 59.

It is to be understood that one arm 45 and its 15 cooperating parts is provided for each pair of polishing wheels 6. The arm is mounted to swing in a plane parallel with and extending between the planes of rotation of the wheels 6 with which 20 it is associated. The wheels 6 of each pair are spaced apart such a distance that stoppers S carried by the spindle 59 associated therewith will rest upon the peripheries of said wheels. Where 25 two pairs of wheels 6 are used two arms 45 are employed and, obviously, the number of stoppers being polished during one operation will equal the number of polishing wheels.

In practice the arms 45 are swung upwardly 25 by means of handles 61 so that the notched ends of the latch levers 52 will snap into engagement with the strip 10, thereby holding the rocker heads 56 in elevated positions. With the parts thus arranged stoppers S to be polished are inserted in the two ends of each spindle 59. The 30 polishing wheels are rotated by suitable mechanism provided for that purpose. The motor 43 and the mechanism controlled thereby will drive shaft 22 which, in turn, will cause the spindles 35 to be rotated simultaneously. The shaft will also transmit motion through worm 21 and gears 15, 16 and 19 to cam 20. This cam will cooperate with roller 23 to slowly reciprocate the revolving shaft 22. Consequently the arms 45 will be reciprocated within a limited area while the spindles 59 are being rotated.

The parts are so proportioned that the path 40 of movement of the reciprocating spindles will be shorter than the width of the polishing faces 45 of wheels 6.

After the spindles have received the stoppers to be polished each of the arms 45 is swung 50 downwardly to bring the edges E of the stopper heads H into contact with the wheels 6. The rocker heads will equalize the pressure of the stoppers upon the wheels 6 and as the wheels are rotating at one speed while the stoppers are 55 rotating at another speed the edges of the stoppers will be quickly polished. Wear upon the wheels will be distributed over the peripheries thereof by the reciprocation of the stoppers during the polishing operation. As the stoppers of one pair become polished the rocker head is raised and held while the finished stoppers 60 are removed and others substituted. Latch lever 52 is then released from strip 10 and the rocker head lowered to bring the newly supplied stoppers into engagement with their polishing wheels. This operation is repeated with 65 the next arm 45 and by properly timing the mechanism the time required to remove a pair of finished stoppers, position additional stoppers in the spindle, and apply them to their polishing wheels, will substantially equal the time required to properly polish those stoppers being 70 acted upon by the other pair of wheels. Thus an operation which is practically continuous can be carried on by one operator and the polishing 75 of the stoppers can be effected at a cost much

less than that which has been possible heretofore.

What is claimed is:

1. A machine for polishing stoppers including 80 a pair of polishing wheels, a shaft mounted for rotation and reciprocation, an arm mounted to reciprocate therewith and swing thereon toward or from the wheels, a rocker head carried by the arm, a rotatable means in the rocker head for holding separate stoppers in contact with the respective wheels, and means for transmitting rotary motion from the shaft to the stopper holding means, said rocker head being mounted for oscillating about an axis extending toward the shaft thereby to maintain the stoppers against the peripheries of their wheels irrespective of differences in the diameters of the wheels.

2. A machine for polishing stoppers including 85 a pair of polishing wheels, an arm mounted for swinging movement toward or from the wheels, rotatable means rockably connected to the arm for holding separate stoppers in contact with the peripheries of the respective wheels, and for equalizing pressure between the held stoppers 90 and their polishing wheels without regard to differences or variations in the diameters and contours of the wheels, and means for rotating the stopper holding means.

3. A machine for polishing stoppers including 100 a pair of polishing wheels, an arm mounted for swinging movement toward or from the wheels, rotatable means rockably connected to the arm for holding separate stoppers in contact with the respective wheels, and for equalizing pressure 105 between the held stoppers and their polishing wheels irrespective of the relative diameters and contours of the wheels, means for rotating the stopper holding means while the stoppers are in engagement with the peripheries of the 110 wheels, and means for reciprocating the stopper holding means transversely of the wheel peripheries during the rotation of said holding means.

4. A machine for polishing stoppers including 115 rotatable polishing wheels, an arm mounted for 120 swinging movement, rockable means carried by and movable about the longitudinal axis of the arm for holding separate stoppers in contact with the respective wheels and equalizing pressure between the stoppers and the peripheries of their 125 wheels irrespective of the relative diameters and contours of the wheels, means for rotating the stopper holding means, means for reciprocating the stopper holding means during the rotation thereof, and means for supporting the stopper holding means and the engaged stoppers out of 130 operative relation with the wheels prior to and during the reciprocation of said means.

5. A machine for polishing stoppers including 135 polishing wheels mounted for rotation, a shaft 140 mounted for rotation and reciprocation, means operated by the rotation of said shaft for reciprocating it, an arm mounted to swing upon the shaft and to reciprocate therewith, a rocker head carried by the arm and movable about an axis extending toward the shaft, a spindle 145 extending across the peripheries of the wheels and supported by and movable with rocker head and having stopper receiving ends for supporting stoppers in contact with the peripheries of the respective wheels irrespective of the relative diameters and contours of the wheels, and means for transmitting rotary motion from the shaft to the spindle.

6. A machine for polishing stoppers including 150

- polishing wheels mounted for rotation, a shaft mounted for rotation and reciprocation, means operated by the rotation of said shaft for reciprocating it, an arm mounted to swing upon the shaft and to reciprocate therewith, a rocker head carried by the arm and movable about an axis extending toward the shaft, a spindle extending transversely of the wheel peripheries and supported by and movable with the rocker head and having stopper receiving ends for supporting stoppers in contact with the peripheries of the respective wheels irrespective of the relative diameters and contours of the wheels, means for transmitting rotary motion from the shaft to the spindle, a stationary member parallel with the shaft, a latch movable with the arm for sliding engagement with said member, said latch and member cooperating to hold the arm elevated during the reciprocation thereof, and means on the arm for disengaging the latch from said member. 5
7. A machine for polishing stoppers including rotatable polishing wheels, means rockable about an axis extending toward the axis of the wheels and bridging the space between the wheels for holding stoppers in contact with the peripheries of the wheels and equally distributing pressure thereto irrespective of the relative diameters and contours of the wheels, and means for rotating said holding means while the stoppers are in contact with the wheels. 80
8. A machine for polishing stoppers including rotatable polishing wheels, means rockable about an axis extending toward the axis of the wheels and bridging the space between the wheels for holding stoppers in contact with the peripheries of the wheels and equally distributing pressure thereto irrespective of the relative diameters and contours of the wheels, and separate means for rotating and reciprocating the stopper holding means while the stoppers are in engagement with the wheels. 85
- 10 to the spindle, a stationary member parallel with the shaft, a latch movable with the arm for sliding engagement with said member, said latch and member cooperating to hold the arm elevated during the reciprocation thereof, and means on the arm for disengaging the latch from said member. 15
- 15 20

7. A machine for polishing stoppers including
